CLAIM

The ornamental design for a string light, as shown and described.

DESCRIPTION

FIG. 1 is a front, right side, top perspective view of a string light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detailed view of the electrical power control box shown in the region 8 of FIG. 1; and,

FIG. 9 is an enlarged detailed view of the last one of the light bulbs forming the string light as shown in the region 9 of FIG. 1.

The dash-dot-dash broken lines encircling the enlarged views in FIGS. 1, 8-9 are for annotative purposes only and form no part of the claim thereof.

The string light is shown with a symbolic break in its length. The appearance of any portion of the article between the break lines forms no part of the claimed design.
